LIFESAVING EQUIPMENT

Fred F. Patten, Woonsocket, R. I., assignor to
 United States Rubber Company, New York,
 N. Y., a corporation of New Jersey

Application October 21, 1942, Serial No. 462,867

3 Claims. (Cl. 244—147)

This invention relates to life-saving equipment for aviators and particularly to life-saving equipment packs adapted to be stored in airplanes so that they can be conveniently attached to the aviator while he is seated without being removed from its stored position.

Heretofore packs for life-saving parachute rafts have been carried either on the back of the aviator, attached to the shoulder straps of the parachute harness or as a seat, attached to the crotch straps of the parachute harness. When the pack is carried on the back, the shoulders of the aviator support the pack at all times while he is in the plane which unduly tires the shoulder muscles, hinders his action, and when the aviator jumps from the plane, the pack is liable to interfere with the opening of the parachute. As a seat pack the raft must be attached to the pilot's parachute or parachute harness and worn by him before taking position in the plane. This unduly burdens the pilot making it difficult for him to walk and climb into the cockpit, and the pack is liable to interfere with the opening of the parachute. Further, when the boat is held in this position, the inflation valve is awkwardly located.

In accordance with this invention the foregoing disadvantages are eliminated by storing and normally directly supporting the pack on a part of the plane, and in such a position that it can be quickly attached to the aviator while he is sitting in his seat. The attaching means are so arranged that the pack is secured to the lower portion of the aviator's harness, either on the side or in front of the aviator. When the pack is in either of such positions, it does not interfere with the operation of the parachute pull string, or the opening of the parachute. Preferably the pack is normally stored and supported on the side or front of the aviator's seat, and may remain so supported after the pack is attached to the harness, and until the aviator is ready to leave his seat. Means are provided for quickly releasing the pack from the seat from the aviator desires to leave it, for example when he is ready to jump from the plane. Further, the inflation valve is readily accessible, and the raft can be inflated and discharged from its pack in one turn or pull of the valve handle.

The invention and its foregoing advantage will be more clearly understood by referring to the following specification and the accompanying drawing, in which:

Fig. 1 is a standing view of an aviator showing

the life-saving equipment embodying this invention secured at the side of the aviator;

Fig. 2 is an isometric top view of the seat in the airplane showing the pack containing and forming a part of the life-saving equipment supported on the side of the seat;

Fig. 3 is a modified form of the invention showing the pack containing the life-saving equipment attached to the front of the aviator in a standing position; and

Fig. 4 is an isometric top view of the seat in the plane showing the life-saving equipment pack attached to the front of the seat, and in position to be attached to the aviator's harness as shown in Fig. 3, but while the aviator is seated.

The life-saving equipment pack may be supported by the plane in any position convenient for attachment to the aviator while so supported, and while the aviator is seated. Referring to Fig.

20 2 of the drawing, the life-saving equipment comprises a pack 10 which contains a parachute life raft. The pack is normally supported by a strap 11 secured to the side 12 of the aviator's seat 13 by screws 14. The strap 11 is provided 25 at its ends with a quickly releasable buckle 15 which is adapted to secure the ends together and the strap around the pack. The strap 16 passes through an eye in a snap hook 17, and each end of the strap is secured to the pack 10 while they 30 extend longitudinally of the pack. One end of a strap 18 is secured to the opposite end of the pack 10 while it extends circumferentially of the pack. A snap hook 19 is secured to the free end of the strap 18. A ring 20 is secured to the pack 10, and 35 the hook 19 is adapted to be snapped into the ring 20.

When the aviator is seated in the plane seat 13 with his parachute harness 21 adjusted on his body, the hook 17 can be attached to the ring 40 22 of the harness, and the strap 18 is adapted to be passed around the leg of the aviator and snapped on the ring 20 as shown in Fig. 1. In the event the aviator desires to stand up, or jump 45 from the plane, he releases the buckle 15, which permits the pack 10 to drop out of the strap 11. When he stands up the pack 10 is secured to the aviator in the position shown in Fig. 1. After jumping the aviator pulls the rip cord and releases the parachute in the usual manner.

In the modification of the invention shown in Figs. 3 and 4, the life-saving equipment pack 23 is attached to the front edge of the plane seat 24 by means of a strap 25 secured to such edge. The 55 strap is provided with a quickly releasable buckle

26, which secures the ends of the strap together and thereby retains the pack 23 within the surrounding strap. The pack 23 is provided with two straps 27 having each of their ends 28 secured to the opposite sides of the pack at each end thereof, while the ends extend radially of the pack and so that the straps extend from the pack transversely to its axis and towards the back of the seat 24. The straps 27 pass through an eye on the snap hooks 29 which are adapted to secure the pack 23 to the harness.

When the aviator is seated in the seat 24, his legs extend over the pack 23, and the snap hooks 29 can be snapped into the rings 30 (Fig. 3) on the parachute harness 31. When the snap hooks 29 are so secured and the aviator desires to leave his seat, he releases the buckle 26, and before or after standing he pulls the pack 23 between his legs so as to position the pack in front of him. Upon standing the pack 23 will drop to the position shown in Fig. 3 in front of the aviator. When the aviator takes the parachute leap, the pack 23 will tend to fly upwards, but the straps 27 are sufficiently short to prevent the pack from striking the aviator in the stomach or face. However, if the aviator desires to stabilize the pack 23 he can do so with his hands, since the pack remains in reach of him.

The packs 10 and 23 being in either of the positions shown in Figs. 1 and 3, they do not interfere with the opening of the parachute. When the aviator strikes the water, or just before he strikes, whether the pack 10 is in the position shown in Fig. 1, or whether the pack 23 is in the position shown in Fig. 3, he can open the packs by unsnapping the fasteners 32 or 33 to permit the removal of the parachute life raft or other life saving equipment that may be contained in the packs. In the event that the life-saving raft is carried, it may be inflated by releasing CO₂ from a container into the raft. The valve for releasing the CO₂ may be located on the raft underneath the pack flap to which the snap fasteners 32 or 33 are affixed, and in such position that it is readily accessible to the aviator, and so that the raft can be inflated with one turn of the valve handle. The inflating pressure will automatically discharge the raft from the pack.

While the preferred forms of this invention have been described, it will be understood that

changes in the details hereof may be made without departing from the spirit of the invention or the scope of the appended claims.

Having thus described my invention, what I claim and desire to protect by Letters Patent is:

1. In combination with an airplane, a life-saving equipment pack for attachment to an aviator while seated in said plane comprising means for securing said pack to a support in the plane while detached from the aviator's harness and in position so that the pack can be attached to the harness of the aviator while the pack is so supported, a strap secured to one end of the pack, said strap being provided with means operable by the aviator for securing said pack to the harness on the aviator at the lower portion of said aviator while he is seated, and means for quickly releasing said means which secures said pack to said support.

2. In combination with an airplane, a life-saving equipment pack for attachment to an aviator while seated in said plane, said equipment pack comprising a strap secured to the top end thereof, said strap having a fastener adapted to be quickly attached to the aviator's harness, at about the waistline, a second strap secured at one end to the bottom end of the pack, said second strap having a fastener secured to its opposite end and adapted to pass around the leg of the aviator, a member secured to the lower end of said pack to which said second fastener is adapted to be attached, means for securing said pack to the side of the seat of the plane to normally support said pack, and means for quickly releasing said last mentioned securing means.

3. In combination with an airplane, a life-saving equipment pack for attachment to an aviator while seated in said plane, means for securing said pack to the front end of a plane seat to normally support said pack while it is being and after it has been attached to said aviator, and means for quickly releasing said securing means, said pack having straps attached to each end thereof, and fasteners secured to said straps and adapted to be brought between the aviator's legs and attached to the aviator's harness in front of said aviator while he is seated.

FRED F. PATTEN.
